UNITED STATES PATENT OFFICE.

JOHN S. CHAMBERS, OF NEW YORK, N. Y., ASSIGNOR TO CHAMBERS VALVE COMPANY,
A CORPORATION OF NEW YORK.

THROTTLE-VALVE.

1,192,862.

Specification of Letters Patent. Patented Aug. 1, 1916.

Application filed October 5, 1915. Serial No. 54,222.

To all whom it may concern:

Be it known that I, JOHN S. CHAMBERS, a citizen of the United States, residing at New York, in the county of New York and 5 State of New York, have invented certain new and useful Improvements in Throttle-Valves, of which the following is a specification.

This invention relates to throttles, and 10 particularly to throttles adapted for use on steam locomotives.

One of the objects of the present invention is to provide a simple and practical throttle of the above character having few 15 parts which will be cheap to manufacture and install.

Another object is to provide a throttle in which the parts are so positioned and arranged as to permit of ready renewal or re- 20 placement as may be necessary.

A further object is to provide a throttle particularly adapted for use in modern locomotives which will be reliable and efficient in use and operation.

25 Other objects will be in part obvious and in part hereinafter pointed out.

With these and other objects in view the invention consists in certain features of construction, combination of elements and arrangement of parts, the preferred form of 30 which will be first described in connection with the accompanying drawings and then the invention particularly pointed out in the appended claims.

35 Referring to the drawings, wherein the same part is designated by the same reference numeral wherever it occurs, Figure 1 is a longitudinal view, with certain parts in section, showing the rear portion of a locomotive boiler with my improved throttle valve and actuating mechanism applied thereto; Fig. 2 is an enlarged sectional plan view of a portion of the actuating mechanism; Fig. 3 is an enlarged vertical sectional view of the throttle valve in closed position; and Fig. 4 is a similar view with the parts in 40 "drifting" position.

As modern locomotives are now being made with the maximum sized boiler, it has 50 become necessary to reduce the size of the steam dome and other upwardly projecting parts in order to maintain the total height of the locomotive within proper limits. The reduction in height of the steam dome has

caused certain objections and inconveniences 55 to arise in properly positioning the throttle therein as has heretofore been customary.

The present invention is designed not only to accomplish the objects above set forth, but also to overcome certain objections incident to installing a throttle within a relatively small steam dome or, if desired, to dispense with the dome entirely.

Referring to the drawings in detail and more particularly to Fig. 1, 10 denotes the 65 rear portion of the boiler shell provided with a steam space or dome 11 and rear wall 12 positioned within the cab and upon which is mounted a throttle bracket or support 13 all of well known construction. Within 70 the dome or steam space of the boiler is positioned an open ended dry pipe 14 extending downwardly to an elbow 15 and thence forwardly to a throttle box 16 containing a throttle valve, which will hereinafter be described in detail. On the opposite side of the throttle is a second elbow 17 and a continuation 18 of the dry pipe which leads forwardly to the superheater or cylinders, as the case may be. It is, of course, to be 75 understood that the various parts of the dry pipe are connected and supported in any desired manner and it is believed to be unnecessary to go into the details of their construction.

85 The throttle, which is shown more clearly in Figs. 3 and 4, comprises the throttle box 16 riveted or otherwise suitably secured in an opening in the upper part of the shell 10 by means of rivets or fastening devices passing through holes 20. An opening 21 at the right of Fig. 3 communicates with the portion 15 of the dry pipe while another opening 22 in the lower part communicates with the part 18 of the dry pipe, the intervening throttle valve being adapted to control the passage of steam from one part to the other. The upper part of the throttle box 16 is provided with an annular shoulder 23 upon which rests a casting or housing 100 90 95 100 containing part of the actuating mechanism. This housing is secured to the throttle box by means of a plurality of threaded bolts 25 passing through an apertured collar 26 of the housing and engaging tapped recesses in the throttle box. These recesses in the present embodiment are six in number and are equally spaced one from

another, thereby to permit the housing 24 to be placed in any one of several positions as may be desired and as will be hereinafter more fully explained. The lower part of the throttle box is also provided with an annular shoulder 27 within which fits a loosely mounted valve seat or ring 28. The term "loosely" is used to distinguish from a "machine" fit and the space between the ring 28 and the throttle box 16 is somewhat exaggerated as shown in the drawings. One object of this loose fit is to permit slight movement of the ring with respect to its co-acting valve and allow uniform expansion under varying degrees of temperature, and to permit a taking up of the strain exerted thereon by the steam at high pressure. When the throttle is closed, the contact at the annular shoulder 27 is sufficiently tight to prevent any material escape of steam therethrough.

The throttle valve coacting with the valve seat or ring 28 is of the balanced piston type and comprises a main throttle valve member 30 and a piston or auxiliary throttle valve member 31. The main throttle valve member is provided with a packing ring 32 at its upper part sliding within the housing 24 and made as near steam tight as possible. The auxiliary throttle valve member 31 is provided with guides 33 on its web loosely fitting within the valve ring 28 as well as an upwardly projecting annular part 34 adapted to have a sliding movement within the lower part of the main throttle valve member 30. Within the main throttle valve member 30 is positioned a relief valve 35 coacting with a central valve seat 36 integrally formed with the web of the main throttle valve member. A plurality of holes 37 are provided in the bearing wall 38 of the main throttle valve member which surrounds the actuating member or stem 40 and other holes 41 are also provided in that portion of the auxiliary valve member 31 immediately above the seating portion. The lower part of the actuating stem 40 is provided with a washer 42 held in adjusted position by means of a nut 43. The upper part of the stem is connected by means of a pivotally attached link 44 with a crank arm 45 mounted at one end of a rock shaft 46 which is adapted to be oscillated from the cab by means of any desired mechanism, but preferably of that type which will be hereinafter described in detail as the same is believed to possess certain obvious advantages. It will thus be seen that when the throttle valve is in closed position as shown in Fig. 3, steam will be positively prevented from passing through the opening 21 and then out through the opening 22 into the dry pipe 18. When, however, the throttle is in drifting position (Fig. 4) as indicated by the dotted lines of the throttle lever in Fig. 1, the crank arm 45 will be

raised slightly or to that position shown in Fig. 4. When moved to this position, the washer 42 will first coat with and raise the downwardly projecting portion of the bearing 38, and thereby raise the main throttle valve member 30 upwardly a corresponding distance. This will permit steam to pass between the coacting portions of the valve members 30 and 31 through the holes 41 and down through the web of the auxiliary valve member to the dry pipe 18. The amount of steam allowed to escape in this manner is only sufficient to break the vacuum produced by the suction of the pistons within the cylinders. It will also be noted that when the throttle valve is in the drifting position, the relief valve 35 carried by the stem 40 is raised from its coacting valve seat 36 and any steam which may have passed the packing ring 32 into the housing 24 is permitted to escape through this valve 35 and out through the opening 37 into the dry pipe 18, or if no steam has had an opportunity to enter the housing past the packing ring, the reverse may take place, thereby to equalize or balance the steam pressure upon the opposite sides of the piston 30.

The actuating mechanism for this throttle is shown more clearly in Figs. 1 and 2. The upper part of the housing 24 is provided with a T-shaped hood 50, one part of which incloses the crank arm 45 and the laterals are open ended and internally threaded, as clearly shown in Fig. 2. If the housing is put on in the position shown, the rock shaft 46 extends outwardly from one of the open ended laterals and a plug 51 is threaded into the opposite one. If however, the casting 24 should be turned through an angle of 180° or if for any reason, it is desired to actuate the throttle on the left hand side of the locomotive, then the rock shaft would pass through the opposite end of the housing and the plug 51 be inserted at the other side. A tube 52 surrounds the rock shaft 46 and has a steam tight threaded connection with the coacting lateral at one end and a similar connection 53 in one portion of a clamp 54 mounted on the side of the boiler transversely opposite the throttle. The rock shaft 46 is provided with an integral collar 55 tapered at one side and coacting with an asbestos or other suitable packing ring 56 held in place by a gland 57. The members 54 and 57 are held together by means of bolts 58. The member 57 is also provided with a chamber at its outer side inclosing packing material 60 bearing against a flange 61 holding the packing 56 in place. A metal block 62 coacts with the packing 60 and holds the same in contact under the action of a coiled expansion spring 63 reacting against a head 64 of the chamber. The outer end of the rock shaft 46 is provided with a downwardly extending crank arm 65 to

which the outer end of an actuating rod 66 is secured. This rod 66 extends backwardly to the rear wall of the boiler where it is pivotally secured at the point 67 to throttle lever 5 68 which in turn is pivoted at the point 70 to the bracket 13 mounted upon the boiler. A locking segment 71 is provided on its lower side with teeth 72 co-acting with a locking dog 73 mounted upon the throttle 10 lever and moved into and out of locking engagement by means of a latch lever 74 adjacent the throttle handle in the usual manner. The upper part of the segment 71 is provided with a single notch with which 15 a detent or dog 75 is adapted to coact only when the throttle is in drifting position. The engineer by means of this notch is able to know when the throttle is in this position. The dog 75 is, of course, of such construction 20 as to be snapped into and out of the notch without any material effort.

The operation and method of using a device of this character, it is thought, is clear from the above description. A brief statement, however, is substantially as follows: When the throttle is absolutely closed no steam is permitted to pass from the boiler to the cylinders and the parts are in the position shown in full lines in Figs. 1 and 3. 30 However, when the locomotive is drifting, the throttle lever is moved to the dotted line position in which the dog 75 engages the drifting notch in the throttle lever segment and the throttle valve itself is in the position shown in Fig. 4, thereby allowing a small amount of steam to pass through the throttle into the dry pipe 18 and thence to the cylinders. This breaks the vacuum which would otherwise occur in the cylinders during the reciprocation of the pistons. The pressure upon the opposite sides of the main throttle valve member 30 is also equalized by steam passing in and out of the openings 37 and valve 35 as may be necessary. If the throttle valve is opened to service position, the washer on the lower part of the stem 40 will coact with the bearing 38 as well as the central portion of the auxiliary throttle valve member 31 and raise 40 both of them the desired amount, allowing the steam to pass freely between the valve seat 28 and the auxiliary valve member 31.

It is thus seen that the present invention provides a simple and practical throttle having few parts which will be cheap to manufacture and install. Access to the throttle valve may be easily obtained by simply loosening the screws 25 and removing the casting 24. Both throttle members and valve 55 seat may then be removed, ground and replaced as desired. The construction is reliable and efficient in use and operation and particularly adaptable for locomotives in which the boilers have reached the limit in height and size. In short the present inven-

tion is believed to accomplish, among others, all of the objects and advantages above set forth.

As many changes could be made in the above construction and many apparently widely different embodiments of my invention could be made, without departing from the scope thereof, it is intended that all matter contained in the above description or shown in the accompanying drawing shall 70 be interpreted as illustrative and not in a limiting sense.

What I claim is:

1. The combination with a boiler having its shell provided with an opening, of a 80 throttle box within the boiler secured in the opening, a dry pipe leading from the steam space of the boiler to the throttle box, a steam pipe leading from the throttle box, a housing outside the boiler, means to secure 85 the housing to the box, and throttle valve mechanism carried by the housing.

2. The combination with a boiler having its shell provided with an opening, of a 90 throttle box secured to the inner side of the shell and surrounding the opening, a dry pipe leading from the steam space of the boiler to the throttle box, a steam pipe leading from the throttle box, a housing, means located exteriorly of the shell to secure the 95 housing to the box and throttle valve mechanism carried by the housing.

3. The combination with a boiler having a shell provided with an opening, a throttle box within the boiler secured in the opening, 100 a dry pipe leading from the steam space of the boiler to the throttle box, a steam pipe leading from the throttle box, a housing extending exteriorly of the shell adapted to close the throttle box, removable means located exteriorly of the shell to secure the housing to the box, and throttle valve mechanism carried by the housing.

4. The combination with a boiler having a shell provided with an opening, a throttle 110 box within the boiler secured in the opening, a dry pipe leading from the steam space of the boiler to the throttle box, a steam pipe leading from the throttle box, a valve seat carried by the box, a housing, means to secure the housing to the box, a valve carried by the housing and adapted to coöperate with the seat to close the throttle, and means mounted on the housing for operating said 115 valve.

5. The combination with a boiler having a shell provided with an opening, a throttle box within the boiler secured in the opening, a dry pipe leading from the steam space of the boiler to the throttle box, a steam pipe 120 leading from the throttle box, a housing outside the shell comprising a portion adapted to extend through the shell and seat in the box, means located exteriorly of the shell for securing the housing in position 125 130

and throttle valve mechanism carried by the housing.

6. In a throttle valve, the combination with a throttle box having an inlet and an outlet opening, of a valve seat located between said openings, a stem, means for reciprocating said stem, a piston loosely mounted on the stem, a valve face formed at one end of the piston, a hollow piston loosely mounted on the first piston and having a seat to coöperate with the valve face on the first mentioned piston, said hollow piston also having a valve face to coöperate with the valve seat of the box, said hollow piston being provided with openings through which steam can pass when the pistons are separated, and means whereby upon the operation of the stem said pistons will be separated to permit the passage of steam through said openings before said hollow piston is moved from its seat on the box.

7. In a throttle valve, the combination with a throttle box having an inlet and an outlet opening, of a valve seat located between said openings, a stem, means for reciprocating said stem, a piston having an extended hub loosely mounted on the stem, a hollow piston having a hub loosely mounted on the hub of the first piston, the hub of the first piston extending beyond the hub of the second piston when the valve is in closed position, means carried by the stem to engage the hubs successively and reciprocate the pistons, said hollow piston being adapted to coöperate with the valve seat in the box at one end and said first piston being adapted to coöperate with the second piston at the other end, a valve seat formed on the hub of the first piston, a valve carried by the stem adapted to coöperate with said last mentioned valve seat, said first hub being provided with openings for the passage of steam when the valve on the stem is raised from its seat said second piston being provided with openings in its periphery through which steam can pass when said pistons are separated, a shoulder carried by the stem and adapted to engage first the hub of the first piston to separate said pistons and then engage the hub of the second piston to raise it from its seat.

8. In a throttle valve, the combination with a throttle valve box having an inlet and an outlet opening, a valve seat located between said openings, a valve adapted to coöperate with said valve seat, a second valve associated with said first valve and adapted to be opened before said first valve is raised

from its seat, a throttle lever for actuating said valves successively, a sector for said lever, teeth on one edge of said sector, a hand operated latch carried by the throttle lever and adapted to engage said teeth, a notch in the opposite edge of the sector, a detent carried by the throttle lever and adapted to engage said notch, said notch being so positioned on the sector that it will be engaged by said detent when the second valve shall have been opened to drifting position.

9. In a throttle valve, the combination with a throttle valve box having an inlet and an outlet opening, a valve seat associated with said box, a valve adapted to coöperate with said valve seat, a second valve associated with said first valve and adapted to be opened, before said first valve is raised from its seat, a throttle lever for actuating said valves successively, a sector for said lever, teeth on one edge of said sector, a hand operated latch carried by the throttle lever and adapted to engage said teeth, a notch on said sector, a detent carried by the throttle lever and adapted to engage said notch, said notch being so positioned on the sector that it will be engaged by said detent when the second valve shall have been opened to drifting position.

10. In a throttle valve, the combination with a throttle box having openings including an inlet and outlet for the steam passing therethrough, of a valve seat associated with one of said openings, a housing closing another of said openings, valve actuating mechanism mounted in said housing, a valve stem connected with said actuating mechanism, a valve on said stem, a piston valve member having a valve seat for said stem valve, said member being loosely mounted upon said stem and adapted to permit the steam to pass through the loose mounting to the housing, a third valve associated with the piston valve member and adapted to coöperate with said first named seat, and means carried by the stem and adapted to engage with said piston valve member and said third valve successively whereby in the operation of the throttle valve steam pressure accumulating in the housing will be released before the third valve is moved.

In testimony whereof I affix my signature in presence of two witnesses.

JOHN S. CHAMBERS.
